[57] **CLAIM**

The ornamental design for a joint for pipe structure, as shown and described.

DESCRIPTION

FIG. 1 is a top, front, and right side perspective view of a joint for pipe structure showing our new design;

FIG. 2 is a top plan view;

FIG. 3 is a front elevational view;

FIG. 4 is a left side elevational view;

FIG. 5 is a right side elevational view;

FIG. 6 is a cross sectional view taken in the direction of the arrows on line 6—6 FIG. 2;

FIG. 7 is a cross sectional view taken in the direction of the arrows on line 7—7 of FIG. 3;

FIG. 8 is a cross sectional view taken in the direction of the arrows on line 8—8 of FIG. 3;

FIG. 9 is a reduced scale environmental perspective view with the broken line showing of a pipe being for illustrative purposes and forming no part of the claimed design; and, FIG. 10 is a reduced scale environmental perspective view with the broken line showing of additional joints and structure being for illustrative purposes and forming no part of the claimed design.
